United States Patent Office

Des. 224,995
Patented Oct. 31, 1972

224,995

BATHROOM CABINET

Clarence E. Harrison, 612 E. Farmers Road,
Seagoville, Tex. 75159

Filed Sept. 21, 1970, Ser. No. 25,103

Term of patent 14 years

Int. Cl. D6—06

U.S. Cl. D6—127

FIG. 1

FIG. 2

FIG. 3

FIG. 4

FIG. 5

FIG. 6

FIG. 1 is a front elevation of a bathroom cabinet with double mirrored doors, showing my new design.

FIG. 2 is a front elevation thereof with cabinet doors in open position showing doors mirrored inside for special viewing.

FIG. 3 is a plan view as seen from top of FIG. 4.

FIG. 4 is a rear elevation thereof.

FIG. 5 is a side elevation thereof.

FIG. 6 is a plan view as seen from the bottom of FIG. 4.

I claim:

The ornamental design for a bathroom cabinet, as shown.
